DELIVERY MECHANISM FOR ICE VENDING MACHINES

Maxwell T. Zeigler, Huntington Park, Calif., assignor, by mesne assignments, to Zeigler Packaged Ice Machinery Corporation, Huntington Park, Calif., a corporation of California

Application January 21, 1932, Serial No. 587,954

15 Claims. (Cl. 312—35)

This invention relates to vending machines, and has for an object the provision of a novel and highly efficient delivery mechanism for machines of this general class.

5 A more detailed object is to provide a delivery mechanism for a vending machine so constructed that it operates quickly, efficiently, and positively, every attention having been paid to so designing the machine that under all normal circumstances 10 of use by the public it will operate to deliver the article or articles intended to be vended, each time a coin or coins of proper denomination are deposited in the coin box provided for the purpose.

15 Another object of the present invention is to provide a delivery mechanism from which it is practically impossible for an unauthorized person to receive any of the articles the machine is intended to vend, without first depositing the necessary coin or coins.

20 A further object is to provide an article-delivering mechanism as described, which is adapted to handle the articles delivered thereby very gently, and thereby avoid danger of breaking or otherwise harming the articles. This feature particularly adapts the machine of the present invention for use in conjunction with machines for vending blocks of ice of predetermined size and weight, although it is to be understood that my improved 25 delivery mechanism is capable of substantially universal application. Hence the delivery mechanism of the present invention may be considered as an improvement over that disclosed in my co-pending application Serial No. 529,105, filed April 30, 1931, now Patent No. 2,074,351.

35 The invention possesses other objects and advantageous features, some of which, with those enumerated, will be set forth in the following description of the invention's particular embodiment which is illustrated in the drawings accompanying and forming a part of the specification.

40 Referring to the drawings:

45 Fig. 1 is a longitudinal vertical sectional view of an ice vending machine which includes a delivery mechanism embodying the principles of the present invention.

50 Fig. 2 is an enlarged longitudinal vertical sectional view taken through the delivery mechanism. A portion of the figure is broken away to reduce its size.

55 Fig. 3 is an enlarged transverse vertical sectional view taken substantially upon the line 3—3 of Fig. 1, with the direction of view as indicated. The extension of the upper chute is omitted from this figure for clearness.

Fig. 4 is a detail view in side elevation of the delivery mechanism. The direction of view is directly opposite to that of Fig. 2.

Fig. 5 is a detail view in transverse vertical section along the axis of one of the multiple operating shafts of the escapement mechanism.

Fig. 6 is a vertical sectional view taken upon the line 6—6 of Fig. 5, with the direction of view as indicated.

Fig. 7 is a sectional view taken upon the line 10 7—7 of Fig. 6, with the direction of view as indicated.

Fig. 8 is an enlarged detail view showing the cooperative relationship between one of the cams of the escapement mechanism and its associated 15 cam followers. This view shows the parts in the respective positions occupied thereby when the lower stop means is in operative position and the upper stop means is withdrawn.

Fig. 9 is a view similar to Fig. 8, but showing 20 the parts in the positions assumed thereby when the lower stop means is withdrawn and the upper stop means is in operative position.

Fig. 10 is an enlarged detail view in elevation of the control switch.

Fig. 11 is an enlarged transverse vertical sectional view taken substantially upon the line 11—11 of Fig. 10, with the direction of view as indicated.

Fig. 12 is a vertical sectional view taken through 30 one of the walls of the housing of the dispensing machine substantially upon the line 12—12 of Fig. 10, and showing the cooperative relationship between the control switch and the trip which is engaged by each vended article as it is released 35 from the machine.

Fig. 13 is a diagrammatic view in perspective, showing the cooperative relationship between portions of my improved delivery mechanism.

The preferred embodiment of my improved delivery mechanism has been illustrated as being applied to and forming a portion of a vending machine indicated in its entirety at 21. Although the delivery mechanism may be employed advantageously with various types of vending machines, 45 the vending machine 21 chosen for illustration is adapted to dispense blocks of ice of predetermined size and weight. It comprises a housing 22 having therein a plurality of spiral chutes 23 and 24 in superimposed relation to each other, each of these chutes being divided by spiral partitions 26 into a plurality of guideways 27. The construction and operation of the housing 22 and chutes 23 and 24 forms a portion of the subject matter 50 of my aforesaid copending application.

All of the guideways 27 of both chutes 23 and 24 lead to a common delivery mechanism 29, whereby articles dispensed from any of the guideways may be discharged from the housing 22 through a passage or opening 31 common to all the guideways. This opening 31 is formed in the front wall 32 of the housing 22. Each of the guideways 27 serves as a magazine adapted to receive and store a plurality of blocks 33, 34, etc., of ice of predetermined size and weight, and, as clearly shown upon Figs. 1 and 2, the floor of each guideway 27 is defined by rollers 36, upon which the blocks are adapted to rest. Hence the blocks tend to move by gravity downwards along the various guideways 27 toward the delivery mechanism 29, to which they are released one at a time by an escapement mechanism indicated in its entirety at 37.

This escapement mechanism 37 is best illustrated upon Figs. 2 to 9 inclusive. The lower end 41 of each chute 23, 24 is deflected downwards at a greater inclination than the remainder of that chute, and each of these deflected portions 41 corresponds substantially in length to the length of one of the blocks 33, 34 of ice, as clearly shown upon Fig. 2. Owing to the greater inclination of the portion 41 of each chute, a block 33 of ice resting upon the inclined portion will lean forwards from the next adjacent block 34 on the same guideway, thereby defining a space 42 between the upper edges of the lowermost block 33 and the next adjacent block 34 upon each guideway, it being understood that these two blocks engage each other at their lower edges 43.

Although each of the chutes 23 and 24 may be divided into any desired number of guideways 27, the modification chosen for illustration includes three guideways 27 in each chute. The escapement mechanism 37 includes a pair of multiple shafts 46 and 47 extending transversely across each chute, these multiple shafts being disposed in parallelism with and preferably closely adjacent each other, as best shown upon Fig. 2. Inasmuch as all of the multiple shafts 46 and 47 are of identical construction, it will suffice for the purpose of the present disclosure to describe but one of them, say, for example, the shaft 47. As illustrated upon Figs. 5 to 7 inclusive, this multiple shaft 47 comprises a shaft or rod 48 extending completely across all three guideways 27 of the associated chute. One end 49 of the rod 48 is journaled in a strip 51 which extends substantially perpendicularly with respect to the inclined portions 41 of both chutes 23 and 24, so as to support the ends 49 of the rods 48 of all four multiple shafts 46 and 47. From the strip 51 the rod 48 extends through the proximal side wall 52 of the associated chute and across all three guideways of that chute to be journaled at 53 in the opposite side wall 54. A tube 56 shorter than the rod 48 is revolvably disposed thereupon, and a second tube 57 which is still shorter is revolvably disposed upon the tube 56. Both tubes 56 and 57, as well as the rod 48, extend through the side wall 52. Each tube 56 and 57 and the rod 48 are provided with individual, L-shaped arms 58, each of which is rigidly secured to the rod 48 or the associated tube 56 or 57, as the case might be, by means of a hub portion 59 encircling and welded or otherwise rigidly attached to the associated supporting member. The arrangement of different lengths of tubes 56 and 57 and rod 48 as above described permits each multiple shaft 46, 47 to support an L-shaped arm 58 over each guideway 27, each of these L-shaped arms being

individually rotatable about the axis of its associated supporting member. Both multiple shafts 46 and 47 associated with each chute are so disposed that they extend transversely over substantially the central portion of the blocks 33 of ice which rest upon the deflected portion 41 of the associated chute as clearly shown upon Fig. 2, and the L-shaped arms which are associated with the lower multiple shaft 47 incline downwards and forwards so that stop means, preferably in the form of a roller 61 carried at the outer end of each L-shaped arm, is adapted to engage the forward face 62 of the block of ice 33 on the associated deflected portion 41. The L-shaped arms carried by the upper multiple shaft 46 are indicated at 63 and extend in the opposite direction as compared with the lower L-shaped arms 58, so that their stop means 61 are adapted to engage the after face 64 of the block 33 (see Fig. 2). Thus it may be seen that the lower arms 58 serve to hold the blocks 33 until the arms are raised, and the upper arms 63 serve to prevent the next adjacent block 34 from moving down onto the deflected portions 41 as the lowermost block 33 is released, the upper arms 63 holding the next blocks 34 until such time as the lower arms 58 are again returned to holding position.

Means are provided for turning the separate elements of each multiple shaft so as to release the blocks 33 from the several guideways in succession. For this purpose crank arms 66, 67, and 68 are provided upon each tube 57, tube 56, and rod 48, respectively. Each crank arm is provided with a roller 69 at its outer end, and all six rollers 69 of each pair of multiple shafts 46 and 47 rest upon a cylindrical cam 71 (see Figs. 3, 8, and 9). Each cam is rotatably carried by a rod 72 which extends between the strip 51 and the side wall 52, and each cam is provided with three pairs of grooves, each pair comprising a long groove 73 and a short groove 74. The parts are so proportioned and arranged that the roller 69 of each crank arm 66, 67, and 68, as the case might be, of the associated lower multiple shaft 47, is adapted to drop into the shorter groove 74 as the associated cam rotates, whereas the roller 69 of each crank arm of the upper multiple shaft is adapted to drop into the longer groove 73 of the associated cam. Each crank arm is provided with a second arm 76 rigid therewith, to the outer end of which a spring 77 under tension is connected. The other end of each spring 77 is connected to a rigid bracket 78, whereby the springs 77 are adapted to continually press the rollers 69 of their associated crank arms against the associated cam 71. Each cam 71 is provided with a sprocket 79, the sprockets 79 being interconnected by means of a driving chain 81 which also is enmeshed upon a sprocket 82 carried by a drive shaft 83 which receives power from a motor 84 and a speed reduction gearing 86. Thus it may be seen that both sprockets 79 are adapted to be rotated whenever the motor 84 is energized, and inasmuch as the sprockets 79 of both cams are of the same size, both cams 71 will rotate at the same rate.

The pairs of grooves 73 and 74 in the cams 71 are so distributed about the peripheries thereof, and the cams 71 are so positioned with respect to each other, that the escapement mechanisms associated with the several guideways are adapted to be actuated in succession, so that a block 33 will be released from each guideway successively, thus insuring that after a block has been released from any one guideway, a block must be subsequently released from each of the other

guideways before another block is again released from the said first actuated guideway. Moreover, the grooves 73 and 74 of each pair are so arranged that the lower arm 58 associated with each guideway is first lifted so as to release the block 33 engaged thereby, and then returned to holding position, after which the associated upper arm 63 is lifted to permit the next adjacent block 34 to move downwards on its guideway into the position previously occupied by the block which has just been released, whereupon the upper arm 63 again returns to holding position.

Inspection of Figs. 8 and 9 shows that the crank arms 66, 67, and 68 carried by both multiple shafts 46 and 47 of each pair extend from those shafts in substantially the same direction. Hence, whenever one of the rollers 69, regardless of whether it is associated with the upper or lower multiple shaft, drops into its associated groove 73 or 74, the associated supporting member of the associated multiple shaft, say, for example, the rod 48, is turned in a clockwise direction as viewed upon Figs. 8 and 9. However, the L-shaped arms 63 of the upper multiple shaft 25 extend in the opposite direction from that in which the L-shaped arms 58 of the lower multiple shaft 47 extend. The result is that when a roller 69 associated with the lower multiple shaft drops into its groove 74, the associated L-shaped arm 63 will be lifted out of holding position, whereas when a roller 69 associated with the upper multiple shaft drops into its groove 73, the associated L-shaped arm 63 will be lowered into holding position. In other words, each lower L-shaped 30 arm is in holding position when its associated cam follower or roller 69 has been removed from its groove 74, whereas each upper L-shaped arm 63 will be in holding position when its associated cam follower 69 has dropped into its groove 73. Figs. 8 and 9 show that the grooves 73 into which the cam followers 69 of the upper multiple shaft are adapted to drop are considerably longer than the grooves 74 associated with the lower multiple shaft. Moreover, the leading end 91 of the groove 73 is in advance of the leading end 92 of the groove 74 on the cam 71, so that as the cam rotates each cam follower 69 which is connected to an upper arm 63 will drop into the groove 73 and thus move the arm 63 to locking position prior to the time at which the cam follower 69 connected to a lower arm 58 drops into its groove 74. Hence the upper arm 63 associated with each guideway will be in holding position before the lower arm 58 releases the lowermost block 33. Moreover, the lower arm 58 is raised to release the block and then returned to holding position before the upper arm 63 is raised, inasmuch as the trailing end 94 of the groove 74 is in advance of the trailing end 93 of the groove 73.

It is for the purpose of permitting the rollers 61 carried by the upper arms 63 to be interposed between the lowermost block 33 and the next adjacent block 34 on each guideway, that the deflected portions 41 are provided. These deflected portions cause the lowermost blocks 33 to tip forward slightly, presenting a space 42 between the upper edges of the two blocks 33 and 34, although the blocks are in engagement with each other at their lower edges, as clearly shown upon Fig. 2. In order to facilitate movement of a block past the upper arm 63 and onto the deflected portion 41 of the associated guideway so as to bring the forward face 62 of the block into engagement with the lower arm 58, I prefer to pro-

vide a guide 95 over each guideway, adapted to engage the top of the block as it moves onto the deflected portion and prevent the upper forward corner of the block from coming into engagement with either of the multiple shafts 46 or 47. Preferably these guides 95 are of resilient material, and are supported at their ends only so that they can give slightly if a block becomes canted between a guide and the rollers 36 of the guideway, thereby insuring that the block will come to rest with its lower surface resting upon all the rollers 36 in the deflected portion 41 of the associated guideway. Otherwise a block might become jammed between the multiple shafts 46 or 47 and the portion of the guideway upon which the block is supported.

All six guideways 27 of the two chutes 23 and 24 are adapted to deliver their blocks of ice by way of a conveyor 96 common to all six guideways. This conveyor extends from a position below the delivery end of the guideways toward the delivery opening 31 in the front wall 32 of the housing 22. Preferably the conveyor 96 is in the form of an endless belt or its equivalent tensioned between pulleys 97 and 98. The forward pulley 97 is journaled for rotation about a fixed axis adjacent the opening 31, whereas the after pulley 98 is mounted upon a bracket 99 which is slidably mounted upon the floor 101 of the housing 22, and is continually urged rearwards away from the front wall 32 by means of a spring 102 so as to keep the conveyor 96 under tension, but to permit yielding thereof as when a block of ice drops thereupon. A guide plate 103 is provided adjacent the opening 31 to slide blocks from a side of 35 the conveyor into registry with the opening 31 so as to avoid the necessity of making the opening 31 to correspond in width to the chutes 23 and 24.

The conveyor 96 receives power to cause the upper run thereof to move toward the opening 40 31, from the same motor 84 as that which drives the cams 71. For this purpose the shaft 83 whereby the sprocket 82 is carried extends beyond the sprocket and into a transmission 104, whereby power from the motor 84 is transmitted to a drive 45 shaft 106 which is connected to the forward pulley 97 of the conveyor 96. Thus it may be seen that whenever the escapement mechanism 37 is operated to permit release of a block of ice, the conveyor 96 is also actuated to convey that block 50 of ice to and through the delivery opening 31.

A closure 107 is provided for the opening 31, and this closure is adapted to be raised by hydraulic mechanism indicated in its entirety at 108. This closure and the operating mechanism 55 therefor are more completely described in my co-pending application Serial No. 529,105, filed April 10, 1931. Suffice it for the purpose of the present disclosure, therefore, to point out that the pump whereby pressure is supplied to the hydraulic 60 mechanism 108 is also connected, as by a shaft 109, to the motor 84, so that as soon as the motor 84 is energized, the pump will be started and pressure supplied to the hydraulic mechanism 108, raising the door 107, so that the block of ice 65 which is shortly thereafter conveyed to the opening 31 will be permitted to pass under the door.

Means are provided for automatically de-energizing the motor 84 immediately a block of ice has been discharged through the opening 31. 70 This mechanism is illustrated upon Figs. 10, 11, and 12, and includes a control switch 111 mounted preferably upon the inner surface of the front wall 32, as illustrated upon Fig. 1. The control switch 111 includes a solenoid 112 which is adapt- 75

ed to be energized by mechanism which has not been illustrated, when a coin or coins of suitable denomination are inserted into a coin box 113 mounted upon the outer surface of the front wall 5 32. Energization of the solenoid 112 causes the armature 114 thereof to be drawn downwards onto the solenoid, tipping a rocker arm 116 which carries the armature 114 at one end and a weight 122 at the other end. The rocker arm 116 is 10 mounted upon a bracket 117, and a mercury switch 118, preferably of conventional design, is mounted upon the rocker arm 116. The parts are so arranged, however, that when the armature 114 is drawn downwards toward the solenoid 112 15 the motion of the rocker arm 116 thus produced will cause similar motion of the mercury switch 118, moving the switch to horizontal position and permitting the mercury 119 thereof to establish electrical communication between the conductors 20 20 121 which lead to the mercury switch 118. The rocker arm 116 and the mercury switch 118 mounted thereon are adapted to be held in horizontal position after the circuit momentarily closed by the dropping of a coin has caused the 25 solenoid 112 to attract armature 114 for an instant. For this purpose a detent 123 is mounted, as by a pivot pin 124, upon a finger 126 which is carried by a shaft 127 extending through a wall of the control switch. The detent 123 is urged 30 to rotate in a clockwise direction, as viewed upon Fig. 11, by means of a spring 128. A trip 129 is pivotally mounted upon a rod 131 in the opening 31 in such position that when a block of ice passes through the opening the trip will be swung 35 in a counterclockwise direction, as viewed upon Fig. 1, and in a clockwise direction, as viewed upon Fig. 12. Rigid with the rod 131 is a crank arm 132 having a pull rod 133 pivoted thereto. This rod 133 is also pivoted to a second crank arm 40 134 which is rigid with the shaft 127. The result of this arrangement is that when the trip 129 is moved by a block of ice in passing through the opening 31, the rod 133 will be pulled downwards, turning the shaft 127 far enough to withdraw the detent 123 from under the rocker arm 116 upon which the mercury switch 118 is mounted. This will permit the mercury switch to return to normal position, i. e., the position in which it is illustrated upon Fig. 10, breaking the electrical 45 connection between the conductors 121, and inasmuch as these are the conductors whereby the motor 84 is energized, this motion of the arm 116 of the control switch results in de-energizing the motor 84. However, when the solenoid 112 is 50 energized, swinging arm 116 in a counterclockwise direction, as viewed upon Fig. 10, the arm 122 will be elevated sufficiently to permit the spring 128 to move the detent 123 under the arm 116, thereby holding the arm 116 elevated with 55 the mercury switch 118 in horizontal position until the trip 129 is engaged by a block of ice passing through the opening 31.

Means are provided for preventing the insertion of coins into the slots 136 of the coin box 113 if 60 all the guideways 27 are empty. Upper and lower shafts 137 and 138 are journaled in the side walls 52 and 54, and extend over the guideways of the upper and lower chutes, respectively. Each shaft 137, 138 is provided with a finger 139 extending 65 downwards therefrom toward each of the several associated guideways, and these fingers 139 are in such position that they are adapted to be engaged by the blocks 33 of ice upon the deflected portions 41 of the guideways. Both shafts 137 and 138 are interconnected by a rod 141, so that

all the fingers 139 are disposed in substantially the same relative position. A spring 142 urges all the fingers 139 to rotate in a counterclockwise direction, as viewed upon Fig. 13, i. e., to press the fingers against the blocks of ice 33. However, inasmuch as all the fingers are interconnected by the rod 141, both shafts 137 and 138 are held against rotation as long as there is a block of ice 33 upon the deflected portion 41 of any one of the guideways. However, as soon as all of the 10 guideways have become empty, or if for any other reason there is not a block 33 upon the deflected portion of at least one guideway, both shafts 137 and 138 will be permitted to be turned by the spring 142. The upper shaft 137 carries a crank arm 143 which is rigid therewith, and this is connected by a rod 144 to a lever 146 which extends through a slot 147 in the top of the coin box 113 and is pivoted at its lower end inside the box. The lever 146 carries a plate 148 which is adapted 20 to be moved under the coin slots 136 when the lever 146 is moved forward, and thereby prevent insertion of coins into the slots 136. However, as soon as a block 33 moves onto any one of the deflected portions 41, the associated finger will 25 be engaged by that block, turning both shafts 137 and 138 to normal position, and withdrawing the plate 148 so that coins then can be inserted into the slots 136. It should be explained that the coin box 113 contains any preferred mechanism (not shown) for completing the circuit between conductors 149 which lead to the solenoid 112 in the control switch 111, this mechanism being actuated whenever coins of the proper denomination are inserted into the slot 136. 30

One of the important features of the delivery mechanism of the present invention is that it is adapted to handle the blocks of ice 33 so gently that there is little danger of their being broken when handled thereby. The delivery end 40 of the lower chute is positioned only a short distance above the conveyor 96, the result being that when a block 33 is released from any one of the three guideways 27 of the lower chute, it will slide forward or tip and drop onto the 45 conveyor 96, but with so little force that the block will not be harmed. The spring 102 will give slightly when the block lands upon the conveyor, thereby breaking the shock of the fall and thus further assisting in avoiding danger 50 of damage to the block. The delivery end of the upper chute, however, is elevated a considerable distance above the conveyor 96, and accordingly I have provided an extension 151 which is hinged to the delivery end of the upper chute and adapted to receive the blocks 33 as they are released 55 therefrom and convey them relatively gently to the conveyor 96. This extension 151 is in the form of a chute or slide hinged as at 152, and of such length that when it swings downwards from the 60 position illustrated upon Figs. 2 and 4 its lower end will rest upon or be positioned closely adjacent the conveyor 96. The extension 151 is normally held in elevated position by yieldable 65 means such as a counterweight 153, the result being that the extension 151 will be retracted out of the path of blocks released from the lower chute. The extension 151 is provided with a dashpot mechanism 154 in the form of a cylinder 156, which is connected by means of a 70 crank arm 157 to the extension 151 in such a manner that the cylinder 156 is adapted to be moved axially upwards when the extension 151 is swung downwards. A piston 158 is fitted within the cylinder 156 with its rod 159 extend- 75

ing through a suitable packing 161 at the upper end of the cylinder, and pivotally connected to a rigid bracket 162 which holds the piston 158 from moving axially. The piston 158 is provided with a suitable check valve 163 which permits hydraulic fluid 164 within the cylinder 156 to move past the piston 158 with relative rapidity when the cylinder moves downwards with respect to the piston, but which permits the fluid to move past the piston only quite slowly when the cylinder moves upwards. Thus it may be seen that when the weight of a block 33 of ice is imposed upon the extension 151, the extension will be swung downwards, but relatively slowly. This causes the block to tip forward, bringing its forward face 62 into engagement with the floor of the extension 151, in which position the block remains motionless with respect to the extension as the extension continues to swing downwards. As soon as the extension has swung downwards far enough to assume a sufficiently inclined position, the block 33 will slide forwards thereupon and come gently to rest upon the conveyor 96 and be conveyed by it to and through the delivery opening 31.

Another detail of construction of my improved delivery mechanism which reduces the possibility of damaging the blocks of ice being handled thereby, is the novel design of roller 61 with which each of the arms 58 and 63 of the escapement mechanism 37 is provided. These rollers serve as the abutment means which prevent further movement of a block of ice after the ice has come to rest thereagainst, and until the abutment means is withdrawn from holding position. Each roller 61 is journaled upon a shaft 166 which extends between fingers 167 at the end of each arm 58. Each roller comprises an inner and outer tube 168 and 169, respectively, preferably of metal, the inner tube 168 being rotatably fitted upon the shaft 166 and the outer tube 169 being of considerably greater inside diameter than the outside diameter of the inner tube 168. This leaves an annular space between the two tubes 168 and 169, and within this space, and preferably filling the same, is a sleeve 171 of resilient material such as soft rubber. This permits the outer tube 169 to move laterally with respect to the inner tube 168, which is held against lateral movement by the shaft 166, and accordingly presents a cushion which is adapted to absorb the shock of engagement of a block of ice which comes into contact with the roller 61 with considerable force.

Operation

When the proper coin or coins are inserted into the coin slots 136, the solenoid 112 will be energized as hereinabove described, swinging the arm 116 downwards and carrying the mercury switch 118 to horizontal position so as to complete the circuit which includes the conductors 121, thereby energizing the motor 84. Even though the solenoid 112 is energized for a relatively short interval of time, the mercury switch 118 remains in circuit-closing position because of the engagement of the arm 116 on top of the detent 123.

Energization of the motor 84 results in supplying fluid pressure to the hydraulic mechanism 108, raising the door 107. At the same time it starts the conveyor 96 into motion, and starts operation of the escapement mechanism 37 by rotating the cams 71.

The result of rotating the cams 71 is to move

one of the shorter grooves 74 under the cam follower or roller 69 of the associated lower multiple shaft, and regardless of whether this follower is mounted upon the rod 48, or one of the tubes 56 or 57 of that multiple shaft, the member which carries this cam follower will be rotated slightly by means of its spring 77, thereby raising the lower L-shaped arm 58 which is carried by that same rod 48 or shaft 56 or 57 as the case might be. This will lift the associated stop roller 10 61 far enough to permit the lowermost block 33 to move off the inclined portion 41 of its guideway and onto the conveyor 96, either directly or through the expedient of the hinged extension 151, depending upon whether it is a lower guideway or an upper guideway from which the block is being released.

Owing to the relative positions of the long and short grooves 73 and 74, respectively, of the cams 71, the stop roller 61 carried by the upper L-shaped arm 63 of the same guideway will be in lowered position before the lower L-shaped arm is raised. Hence the next block 34 upon the guideway will be permitted to follow the block 33 which is being released only until the block 34 25 comes into engagement with the upper stop roller 61. However, upon continued rotation of the cams, the trailing end 94 of the groove 74 will move under the associated cam follower or roller 69 of the lower arm, causing the lower arm again 30 to be moved to holding position and subsequently the trailing end 93 of the groove 73 will move under the cam follower connected to the upper arm 63, causing that arm to be raised, and thereby permitting the next block 34 to move onto the 35 inclined portion 41 of the guideway and into engagement with the lower stop roller 61 in readiness to be released the next time the lower stop roller 61 is raised. However, before this same lower stop roller is raised, releasing another block 40 from the same guideway, one block will have been released from each of the other guideways, owing to the relative arrangement of the grooves 73 and 74 of the two cams 71.

The motor 84 will continue in operation until 45 a block of ice which has been delivered to the conveyor 96 from one of the guideways, is carried to and through the opening 31 at least far enough to cause actuation of the trip 129. When this occurs the finger 126 and detent 123 will be 50 withdrawn from under the arm 116 on which the mercury switch 118 is mounted, owing to the connection between the finger 126 and the trip 129 by means of the rod 133. This will permit the mercury switch 118 to return to tipped position as illustrated upon Fig. 10, interrupting the 55 circuit of motor 84 and causing all portions of the delivery mechanism to come to rest. When a block of ice has been advanced by the conveyor 96 far enough to engage the trip 129 it will be 60 in such position that it can easily be removed from the vending machine.

It will be observed that it is not necessary for a purchaser to wait, after having deposited the proper coins, long enough for the actuation of the 65 escapement mechanism 37 to release a block of ice onto the conveyor 96 and to convey that same block to the opening 31. It is entirely possible for the delivery mechanism to come to rest with one or more blocks resting upon the conveyor 96, 70 so that the next time the machine is started in operation it will be necessary for it to operate only long enough to convey that block which is nearest the front wall 32, to the trip 129 before that block can be removed from the machine by 75

the purchaser. As this occurs another block probably will be released by the escapement mechanism 37 onto the conveyor 96, where it will come to rest as soon as the trip 129 has been engaged, 5 leaving the block which has just been released from one of the guideways, upon the conveyor 96 and in readiness to be dispensed upon subsequent operation of the machine.

Should all the guideways 27 become emptied of 10 blocks of ice, or conditions be such that no block will be in a position to be delivered from the lower end of any guideway, the fingers 139 and their supporting rods 137 and 138 will be swung by the spring 142 thereby causing the plate 148 to be 15 moved across the coin slots 136, making it impossible for a person to insert coins into the coin box. This closing of the coin slots, however, will not occur unless all the guideways have become emptied or unless other cause develops for failure. 20 Use of the arrival of a block 33 upon the inclined portion 41 of at least one of the guideways. If it should happen that an unequal number of blocks are loaded into the different guideways, causing one or more of the guideways to become 25 emptied before the others, the machine can still be operated until the last guideway having blocks of ice therein, and with at least one block of that guideway advanced to the extreme lower end thereof, also becomes emptied. This follows from 30 the fact that the shafts 137 and 138 are not permitted to turn until such time as no one of the guideways has a block 33 upon the inclined portion 41 thereof. As soon as this occurs, the shafts 137 and 138 will turn and cause the coin slots 136 35 to close. This will insure that the purchaser receive a block of ice if he deposits a coin or coins, because the cams 71 will continue to rotate, thus causing actuation of the upper and lower stop arms 58 and 63 of the several empty guideways in 40 succession until a block of ice is delivered by the conveyor 96 to the opening 31, where it engages the trip 128 and causes de-energization of the motor.

It is to be understood that the details of the 45 invention, as herein disclosed, are subject to alteration within the spirit or scope of the appended claims.

I claim:

1. In a vending machine, an inclined chute 50 adapted to receive articles to be vended, upper and lower stop means normally lying in the path of articles on said chute, said lower stop means normally engaging the forward face of one of said articles and said upper stop means normally 55 being disposed between said article and the next adjacent one of said articles, means operative to withdraw said lower stop means to release the article engaged thereby and then return said lower stop means to normal position, means operative subsequently to replacement of said upper stop means to permit said next adjacent article to move into engagement with said lower stop means and then return said upper stop means to 60 normal position, and resilient guide means engaging the top of the article as it moves into engagement with said lower stop means.

2. In a vending machine, an inclined chute 65 adapted to receive articles to be vended, an movable portion of said chute being deflected to 70 present a space between corresponding edges of two of said articles when one of said two articles moves onto said deflected portion, upper and lower stop means normally lying in the path of said articles, said lower stop means normally

engaging the forward face of an article upon said deflected portion of said chute and said upper stop means normally extending into said space, means operative to withdraw said lower stop means to release the article on said deflected portion and then return said lower stop means to normal position, and means operative subsequently to replacement of said lower stop means for withdrawing said upper stop means to permit the next of said articles to move onto said deflected portion and then return said upper stop means to normal position. 10

3. In a vending machine, an inclined chute adapted to receive articles to be vended, a portion of said chute being deflected to present a space 15 between corresponding edges of two of said articles when one of said two articles moves onto said deflected portion, upper and lower stop means normally lying in the path of said articles, said lower stop means normally engaging the forward face of an article upon said deflected portion of said chute and said upper stop means normally extending into said space, means operative to withdraw said lower stop means to release the article on said deflected portion and then return said lower stop means to normal position, means operative subsequently to replacement of said lower stop means for withdrawing said upper stop means to permit the next of said articles to move onto said deflected portion and then return said upper stop means to normal position, and resilient guide means engaging the top of said article as it moves onto said deflected portion. 20

4. In a vending machine, an inclined chute 35 adapted to receive articles to be vended, and means for releasing one of said articles at a time comprising upper and lower rods extending transversely with respect to said chute, an angular arm rigid with each of said rods and having its end deflected into the path of said articles, the end of said lower arm normally engaging the forward face of one of said articles and the end of said upper arm normally being disposed in front of an article behind that engaged by said 40 lower arm, means operative to turn said rods to withdraw said lower arm to release the article engaged thereby and then return said lower arm to normal position, and means operative subsequently to replacement of said lower arm 45 for turning said upper rod to withdraw said upper arm and then return it to normal position. 50

5. In a vending machine, an inclined chute adapted to receive articles to be vended, and means for releasing one of said articles at a time 55 comprising upper and lower rods extending transversely with respect to said chute, an angular arm rigid with each of said rods and having its end deflected into the path of said articles, the end of said lower arm normally engaging the forward face of one of said articles and the end of said upper arm normally being disposed in front of an article behind that engaged by said lower arm, a cam, rotating means therefor, and a lever rigid with each of said rods and having means thereon engaging said cam, said cam being adapted to turn said lower rod to withdraw the arm thereon and release the article engaged thereby and then return said lower rod to normal position, and said cam 60 also having means thereon operable subsequently to the return of said lower rod for turning said upper rod to withdraw the arm thereon and then return the upper rod to normal position. 65

6. In a vending machine, an inclined chute 70

- adapted to receive articles to be vended, a portion of said chute being deflected downwards to present a space between the upper edges of two of said articles when one of said two articles moves onto said deflected portion, upper and lower rods extending transversely of said chute above the deflected portion thereof, an angular arm rigid with each of said rods and having its end deflected into the path of said articles, 5 the end of said lower arm normally engaging the forward face of an article on the deflected portion of said chute and the end of said upper arm normally extending into said space, means operative to turn said rods to withdraw said 10 lower arm and release the article on said deflected portion and then return said lower arm to normal position, and means operative subsequently to replacement of said lower rod for turning said upper rod to withdraw said upper arm 15 and then return it to normal position.
7. In a vending machine, an inclined chute adapted to receive articles to be vended, a portion of said chute being deflected downwards to present a space between the upper edges of two 20 of said articles when one of said two articles moves onto said deflected portion, upper and lower rods extending transversely of said chute above the deflected portion thereof, an angular arm rigid with each of said rods and having its 25 end deflected into the path of said articles, the end of said lower arm normally engaging the forward face of an article on the deflected portion of said chute and the end of said upper arm normally extending into said space, a cam, 30 rotating means therefor, and a lever rigid with each of said rods and having means thereon engaging said cam, said cam being adapted to turn said lower rod to withdraw the arm thereon and release the article on said inclined portion and 35 then return said lower rod to normal position, and said cam also having means thereon operable subsequently to the return of said lower rod for turning said upper rod to withdraw the arm thereon and then return the upper rod to normal 40 position.
8. In a vending machine, a chute, means dividing said chute into a plurality of guideways, each 45 of said guideways being adapted to receive a plurality of articles to be vended, upper and lower multiple shafts extending transversely of said chute, each comprising a rod extending from adjacent one side of said chute to a position over the distal guideway, and a tube associated with each of the other guideways, said shaft and tubes being disposed coaxially and each tube extending from the said side of said chute to a position over the associated guideway, said rod and tubes of each 50 multiple shaft each having an angular arm rigid therewith over the associated guideway, the arms of said lower multiple shaft normally engaging the forward faces of the lowermost articles on said guideways and each of the arms of said upper multiple shaft normally being disposed in front of an article behind the lowermost articles 55 on the associated guideway, means at a side of said chute for successively turning the tubes and rod of said lower multiple shaft to withdraw the associated arms to release in succession the articles engaged thereby and then return the arms 60 to normal position, and means at said side of said chute for turning the tubes and rod of said upper multiple shaft to withdraw the arms thereof and then return them to normal position, each upper arm being withdrawn subsequently to return of 65 the associated lower arm to normal position.
9. In a vending machine, a chute, means dividing said chute into a plurality of guideways, each of said guideways being adapted to receive a plurality of articles to be vended and each guideway having its end deflected downwards to present a space between the upper edges of two of said articles thereon when one of said two articles is disposed upon said deflected portion, upper and lower multiple shafts extending transversely of said chute, each comprising a rod extending from 10 adjacent one side of said chute to a position over the distal guideway, and a tube associated with each of the other guideways, said rod and tubes being disposed coaxially and each tube extending from the said side of said chute to a position over 15 the associated guideway, said rod and tubes of each multiple shaft each having an angular arm rigid therewith over the associated guideway, the arms of said lower multiple shaft normally engaging the forward faces of articles on said deflected portions of said guideways and each of the arms of said upper multiple shaft being normally disposed within said space defined by articles on the associated guideway, means at a side of said chute for successively turning the 20 tubes and rod of said lower multiple shaft to withdraw the associated arms to release in succession the articles engaged thereby and then return the arms to normal position, and means at said side of said chute for turning the tubes and rod of 25 said upper multiple shaft to withdraw the arms thereof and then return them to normal position, each upper arm being withdrawn subsequently to return of the associated lower arm to 30 normal position.
10. In the escapement means of a device for dispensing articles, stop means adapted to be engaged by said articles and comprising arms having means for engaging the front and the rear faces respectively of said articles, said front and 35 rear faces being disposed transversely to the direction of movement of said articles, and guide means comprising a leaf spring for engaging the top of the articles as they are engaged by said stop means.
11. In a dispensing mechanism, a housing, an inclined chute in the housing, a door providing egress from the housing, a conveyor leading from the bottom of the chute to the door, escapement means for releasing articles one at a time from 40 the chute, and means for opening the door, starting the conveyor and operating the escapement means to release an article from the chute to be deposited on the conveyor and carried thereby to the opened door.
12. In a dispensing mechanism, a housing, an inclined chute in the housing, a door providing egress from the housing, a conveyor leading from the bottom of the chute to the door, escapement means for releasing articles one at a time from 45 the chute, and unitary drive means for opening the door, starting the conveyor and causing the escapement means to release an article from the chute so as to be deposited on the conveyor and carried thereby to the opened door.
13. In a dispensing mechanism, a housing, a plurality of inclined chutes in the housing, a door providing egress from the housing, a conveyor leading from the lower ends of the chutes to the door, escapement means at the lower end 50 of each chute, and means for opening the door, starting the conveyor, and causing the escapement means to release an article from a chute in sequence upon each opening of the door.
14. In a dispensing mechanism, a housing, a 55

plurality of inclined chutes in the housing, a door providing egress from the housing, a conveyor leading from the lower ends of the chutes to the door, escapement means at the lower end of each chute, and unitary drive means for opening the door, starting the conveyor and causing the escapement means to release an article from a chute in sequence upon each opening of the door.

5. In a dispensing mechanism, an inclined chute having its lower end of greater inclination

than the balance of the chute, rock shafts rotatably mounted over the lower end of the chute, arms carried by the rock shafts engageable with the front and back sides of an article positioned on the lower end, and means for rotating the 5 rock shafts independently of each other so as to swing the arms into and out of the path of an article passing along the chute.

MAXWELL T. ZEIGLER. 10
